UNITED STATES PATENT OFFICE.

ROBERT S. BOLGER, OF NEW YORK, N. Y., ASSIGNOR OF ONE-HALF TO CHARLES LEFFLER & COMPANY, A CORPORATION OF NEW YORK.

METHOD OF FORMING BOXES AND TUBES.

1,090,593.

Specification of Letters Patent. Patented Mar. 17, 1914.

Application filed February 1, 1912. Serial No. 674,697.

To all whom it may concern:

Be it known that I, ROBERT S. BOLGER, a citizen of the United States, residing at the city of New York, in the borough of Queens and State of New York, have invented certain new and useful Improvements in Methods of Forming Boxes and Tubes, of which the following is a full, clear, and exact description.

10 This invention relates to a novel method of forming paper and cardboard tubing or boxes such as are used for example for the preservation and shipment of incandescent mantles, bottles, and like fragile articles. 15 Heretofore it has been customary to wrap paper, fiber, cardboard, strawboard, or like material, upon mandrels in forming mailing tubes or boxes, the paper being fed to the mandrel in the form of a strip. Thereafter 20 for the purpose of stiffening the tube or box and also for the purpose of providing cushioned walls for the same, it has been customary to insert longitudinally a cylinder of corrugated paper or cardboard; the corrugations extending usually longitudinally of 25 the cylindrical box or tube. This method of constructing devices of this character involves several steps and consumes time and labor which it is the purpose of my present 30 invention to obviate. I furthermore aim to improve the quality of the product, both in strength and appearance. These and other objects of my invention will be hereinafter referred to and the novel method and means 35 whereby they may be attained will be more particularly set forth in the claims appended hereto.

I am aware that my novel process may be effectuated in a variety of ways without departing from the spirit of my invention and that the product may be modified to a considerable extent within the purview of the said invention, and hence desire to be limited only by the scope of the said appended 45 claims.

In the drawings which form a part hereof and in which like reference characters designate like parts throughout the several views, I have exemplified certain preferred 50 forms of product and a preferred method of producing the same.

Referring to the drawings: Figure 1 is a perspective view of a double-back cylindrical

box constructed in accordance with the principles of my invention, portions of the structure being broken away for the purposes of illustration. Fig. 2 is a vertical median section of the device shown in Fig. 1. Fig. 3 is a section similar to Fig. 2, but of a tube instead of a box, the tube in this case being 60 of the single-back type. Fig. 4 is a view similar to Fig. 1 of the said single-back tube. Fig. 5 is a section of the device shown in Fig. 1, the section being taken on line V—V of Fig. 2. Fig. 6 is a similar section taken 65 on line VI—VI of Fig. 3. Fig. 7 is a blank or web from which is made the body of the double-back box shown in Fig. 1. Fig. 8 is an edge view of said blank. Fig. 9 is a blank or web for the single-back tube shown 70 in Fig. 3. Fig. 10 is an edge view of said blank. Fig. 11 is a blank for a double-back tube. Fig. 12 is an edge view of the same. Fig. 13 is a perspective view of the said 75 double-back tube. Fig. 14 is a vertical median section of the same. Fig. 15 illustrates a step in the process of forming a box or tube. Fig. 16 illustrates a second step in the said process. Fig. 17 illustrates the step of completing a single-back box or tube, 80 and Fig. 18 illustrates a portion of the method of making a double-back box or tube.

Referring first to Figs. 1, 2 and 5, it will be observed that the box therein shown comprises preferably a plurality of outer layers of non-corrugated material. Within these outer layers is an intermediate cylindrical wrapping 2 which is corrugated longitudinally in the direction of the axis of the box and within this corrugated wrapping is a layer 3 of preferably plain or non-corrugated strip material. The corrugated and inner plain portions respectively designated 2 and 3 are, in this particular form of the device, of somewhat less height 95 than the plain outer portion or layers 1, so that as seen in Figs. 1 and 2 space is afforded at the bottom of the box for the insertion of an inverted cup-shaped bottom 4 which engages the plain cylindrical inner 100 wall of the outer layer 1. There is also provided a space A due to the fact that the upper edge of the corrugated and interior portions do not reach the upper edge of the layers 1, which permits of inserting a drop-light Welsbach mantle into the box and 105

supporting the same upon the upper edge of the inner wrapping 3. The usual cap 5 may of course be applied to the tube of the box to afford a closure therefor, but since this cap forms no part of the present invention it has been merely indicated in dotted lines in Fig. 2.

The tube shown in Figs. 3, 4 and 6 is of very similar construction to the box shown in Fig. 1, save that in this instance there is no bottom 4 nor inner wrapping 3. The outer layers 1, of which there are two in this instance, surround a single corrugated wrapping 2' which, it will be noted in this case, is of the same width as the layers 1. What I particularly wish to direct attention to is the fact that in both of these forms of device the successive layers or wrappings, whether plain or corrugated, are integrally united, and, as will presently be shown, such a box or tube is formed from a single strip.

Referring to Figs. 7 and 8, I have shown a blank from which the body of the box may be wrapped. This blank is in the form of a single, somewhat elongated strip and by reason of the product sought in this particular instance, to wit, a box for incandescent mantles, this strip is made narrower along a portion of its length, the wide portion, designated 1, corresponding to the material designated 1 in Figs. 1 and 2, while the corrugated and somewhat narrower portion 2 corresponds to the corrugated portion 2 in said first mentioned figures; while similarly the narrow plain portion 3 corresponds to the inner lining of the box. The blank from which the tube shown in Figs. 3 and 4 is formed, is shown in Figs. 9 and 10. The blank is, in this instance, of uniform width, corresponding with the uniform width of the several layers, corrugated and plain, in the said tube. Here again the plain outer wall-forming portion has been designated 1 and the corrugated portion 2'. If it is desired to form a double-blank mailing tube such as is shown in Figs. 13 and 14, the blank will assume the form shown in Figs. 11 and 12. Herein again the outer wrappings have been designated 1, the corrugated section 2, and the inner plain layer or lining 3'.

Since all parts of the body of the box or tube, as the case may be, are integrally united or connected together, it is possible to wrap them around a mandrel, one on top of the other, and thus assemble said body in practically one operation.

While the corrugated portion of the strip may be formed in the blank and before attempting any wrapping operation of the same I prefer to form this corrugated section during the procedure of wrapping the strip upon the mandrel. As shown in Fig. 15, two rolls, respectively designated 10 and 11, are adapted for engagement with each

other, the engaging surfaces being corrugated or toothed as shown. The said rolls are preferably heated when in use and may be rotated in any suitable manner, as by means of a handle 12.

I have purposely avoided any very full illustration of mechanism for accomplishing the present process, since it is obvious that it may be effected manually, although in practice of course a suitable machine will be provided for carrying it out.

As shown in said Fig. 15 the rolls have been moved substantially into engagement with each other so as to firmly press the strip, broadly designated 13, therebetween and the said rolls have been in this case rotated through almost 360°, thereby corrugating a portion of the said strip 13 in the manner shown. While the rolls are being rotated, adhesive material may be applied to the outer surface of the corrugated portion, this material being supplied from some suitable source of adhesive, as for example the paste brush 14. If it be desired to form a single-corrugated layer or wrapping, the rolls will be stopped when they have been advanced but slightly farther than the position shown in Fig. 15. Thereafter one or the other of these rolls may be moved away from its engagement with the co-acting roll, as shown in Fig. 16, wherein the roll marked 11 has been dropped out of engagement with the strip 13. Thereafter the roll 10 is rotated in the same direction in which it had previously been rotated, while the paste or other adhesive is applied to the outer surface of the strip 13 so that the plain or non-corrugated portion of the strip which is wrapped around the corrugated section, which we may here identify as 2', forms the non-corrugated or outer layers 1, previously referred to. During this operation pressure may be applied to the outer surface of the plain section of the strip as by means of a pressure roll 15 or in any other suitable manner, to insure proper engagement between the several contacting parts. When the strip 13 has been almost completely wound into position, the paste brush, if this be the source of adhesive employed, may be removed, as shown in Fig. 17, and the end of the strip may then be rolled by means of the pressure roll 15 around into firm engagement with the adjacent layer or wall 1, completing the tube. The tube is then removed from the mandrel and presents substantially the appearance of that shown in Fig. 4. In shaping a box such as is shown in Fig. 1, the procedure is the same, save that roll 11 is not drawn up into engagement with the roll 10 until after a plain section 3 of the body has been wrapped around the mandrel. If it be desired to have but a single layer 3; after the mandrel has been rotated through a single turn, the cor-

rugged portion formed between the rolls 10 and 11 is fed thereupon.

It is obvious of course that the box shown in Fig. 1 may be formed upon the rolls 5 shown in Fig 15, but I prefer to provide a mandrel 16, in such case, separate and distinct from the heated corrugating rolls in the manner shown in Fig. 18. Herein the adhesive is applied as by means of a paste 10 brush 14 to that portion of the strip between the mandrel 16 and the roll 10. The roll 10 in this arrangement is rotated by means of the handle 12 and the lower roll 11 is slidably journaled as at 17, a lever 18 15 serving to affect the upward displacement of said lower roll when desired, the roll falling by gravity when the hand is removed from the lever 18.

It is obvious of course that the box or tube 20 may have the cushioning or cellular portion thereof formed other than corrugated, and I hence do not desire to be limited to such particular form or disposition of the material of which such section is composed. I 25 have hence applied the term "waved" to this surface, the significance of the term being that portions of said surface are struck up laterally so as to form a series of cush-

ions, no matter how said cushions may be disposed.

Having described my invention, I claim:

1. The method of forming bodies for boxes, tubes and the like consisting in pressing lateral projections into limited portions of a continuous strip of sheet material leaving the remainder of the strip plain and then wrapping or rolling said strip upon itself to form at least one complete layer of plain material and at least one complete layer of the projection bearing material substantially as described. 35

2. The method of forming bodies for boxes, tubes and the like, consisting in corrugating the middle portion of a continuous strip of material leaving the end portions 45 plain, then wrapping or rolling the strip upon itself thereby superposing alternate layers of plain and corrugated material, substantially as described.

In witness whereof, I subscribe my signature, in the presence of two witnesses.

ROBERT S. BOLGER.
